(57) **CLAIM**

I claim the ornamental design for a low visibility aerodynamic antenna housing, as shown and described herein.

DESCRIPTION

FIG. 1 is a left front perspective view of a low visibility aerodynamic antenna housing showing my new design; FIG. 2 is a front elevational view thereof; FIG. 3 is a left side elevational view thereof, the right side elevational view being a mirror image thereof; and, FIG. 4 is a top plan view thereof. The broken line portions of the disclosure are for illustrative purposes only and form no part of the claimed design.
